HAMMER TYPE STAPLER

Morris Abrams, Brooklyn, N. Y., assignor to
 Arrow Fastener Co., Inc., Brooklyn, N. Y., a
 corporation of New York

Application August 17, 1951, Serial No. 242,246

36 Claims. (Cl. 1—49)

1
 This invention relates to hammer type staplers or tackers.

An object of this invention is to provide a stapler or tacker of the character described comprising a frame having a handle extension, a plunger slidably mounted on the frame, a driver bar pivoted to the frame at its rear end and having at its front end a portion adapted to strike the surface which receives the staple, and a driver lever pivoted medially the ends thereof to the frame and pivotally connected at its rear end to an intermediate portion of the driver bar and engaging at its front end, the staple plunger, the arrangement being such that when the tacker is struck against a surface, the driver bar is rotated about its fulcrum to cause rotation of the driver lever, which in turn causes the plunger to descend for driving a staple.

A further object of this invention is to provide a hammer-type stapler or tacker of the character described which is so arranged that a little movement of the driver bar will cause a fast movement of the plunger through a greater distance, thereby giving proper momentum necessary to drive the staple.

Yet a further object of this invention is to provide a hammer-type stapler or tacker of the character described in which the driver bar is relatively long and its rear pivoted end is disposed well in back of the driver lever, and the driver lever having a relatively short arm pivoted to the driver bar and a longer arm engaging the plunger, the arrangement being such that when the tacker is struck a staple is driven with considerable force to insure proper driving of the staples.

A further object of this invention is to provide in a stapler or tacker of the character described, a driver bar having a flat striking surface at its front end so arranged that it will not dig into the material of the surface struck, said flat surface furthermore being inclined forwardly and upwardly when the handle of the tacker is in horizontal position, and when said flat surface is flat against the surface to be struck the handle is inclined upwardly and rearwardly so as to give space for the fingers of the hand holding the handle after fully striking, to make for more comfortable use of the tacker.

Yet a further object of this invention is to provide in a device of the character described, a front cover having a forwardly and upwardly tapered lower end which follows the taper of the striking surface of the driver bar after striking, the arrangement being such that the

front cover and the driver bar together absorb the shock at the end of the stroke.

Still a further object of this invention is to provide in a device of the character described, a top cover cap which can be used as a hammer when the tacker is turned around, said top cover cap having means to interlock with the front cover and being further provided with a rear extension to cover the top of the frame.

Yet a further object of this invention is to provide in a tacker of the character described, a unit fixed in the front of the frame which shall have means to serve as a back stop for the plunger, means to serve as a bottom stop for the plunger, and which shall also serve to hold down a filler channel forming part of a staple magazine for said device.

Yet another object of this invention is to provide in a tacker of the character described, a frame, a combination back and bottom plunger stop fixed within the frame, and a front cover fixed to the frame, and a pin serving to attach the front cover to the frame, and also to sustain the inner back stop for the plunger within the frame, and also to act as a bottom stop for the driver lever, the arrangement being such that the driver lever will hit the pin before hitting the bottom stop until the pin wears.

Yet a further object of this invention is to provide a strong, rugged and durable hammer type tacker of the character described, which shall be relatively inexpensive to manufacture, which shall be sure and positive in operation, easy to manipulate, and yet practical and efficient to a high degree.

Other objects of this invention will in part be obvious and in part hereinafter pointed out.

The invention accordingly consists in the features of construction, combinations of elements, and arrangement of parts, which will be exemplified in the construction hereinafter described, and of which the scope of invention will be indicated in the following claims.

In the accompanying drawings in which are shown various illustrative embodiments of this invention,

Fig. 1 is a longitudinal vertical cross-sectional view of a hammer type tacker embodying the invention;

Fig. 2 is a view similar to Fig. 1 but showing the position of the parts after fully striking the tacker against a surface;

Fig. 3 is a bottom plan view of the device shown in Fig. 1;

Fig. 4 is a partial side elevational view of said tacker with parts broken away and in cross-section;

Fig. 5 is a cross-sectional view taken on line 5—5 of Fig. 2;

Fig. 6 is a cross-sectional view taken on line 6—6 of Fig. 1;

Fig. 7 is a front end view of the device embodying the invention;

Fig. 8 is a cross-sectional view taken on line 8—8 of Fig. 4;

Fig. 9 is a cross-sectional view taken on line 9—9 of Fig. 1;

Fig. 10 is a cross-sectional view taken on line 10—10 of Fig. 1;

Fig. 11 is a cross-sectional view taken on line 11—11 of Fig. 1;

Fig. 12 is a cross-sectional view taken on line 12—12 of Fig. 1; and

Fig. 13 is a cross-sectional view taken on line 3—13 of Fig. 2.

Referring now in detail to the drawing, 10 (Fig. 2) designates a hammer type stapler or tacker embodying the invention. The same comprises a combination frame and handle member 11. Said member 11 comprises a bottom wall 12 from which extend upwardly a pair of parallel side walls 13 (Fig. 1). The bottom wall 12 has a rear edge 14. Said bottom wall 12 is formed, forwardly of its rear edge 14, with an H-shaped cutout or opening 16 (Fig. 3) forming a pair of tongues 17 projecting toward each other, and pairs of spaced shoulders 18 on opposite sides of the tongues 17. At its front end said wall 12 is formed with a forwardly projecting tongue 19 and a pair of aligned spaced shoulders or edges 20 spaced rearwardly of the tongue 19.

The side walls 13 (Fig. 1) are similar to each other and have at their rear ends, upper edges 21 parallel to the bottom wall 12. The upper edges 21 extend from the rear end edges 22 of said side walls 13 forwardly about one-half the length of said side walls, forming portions 23 of uniform height. At the forward ends of the edges 21 are upwardly curved edges 24, and extending from the curved edges 24 are upwardly and forwardly inclined edges 25, terminating in upwardly curved edges 26. Extending forwardly from the upper end of each curved edge 26 is a top horizontal edge 27. Extending downwardly from the forward end of each top horizontal edge 27 is a front vertical edge 28 (Fig. 4). The edges 28 are disposed forwardly of the tongue 19.

It will now be observed that the side walls 13 of the frame 11 have front generally triangular portions 30 (Figs. 1 and 4) which extend from the rear or handle portions 23 of the frame. At the front of the triangular portions 30 are generally rectangular portions 31 (Fig. 4). The side portions 31 of the side walls 13 are formed with aligned horizontal slots 32 extending rearwardly from the front edges 28, for the purpose hereinafter appearing.

The side wall portions 31 are furthermore formed with outwardly pressed extrusions or prongs 33 (Figs. 2 and 8) below the upper end edges 27, for the purpose hereinafter appearing. The extrusions 33 are disposed rearwardly of the front edges 28.

The side walls 13 of the frame are formed with through openings 35 concentric with the curved edges 24 (see Fig. 10). The edges 25 (Figs. 1 and 2) of the triangular portions 30 are furthermore formed near their upper ends with aligned for-

wardly extending notches 36, for the purpose hereinafter appearing. Said side walls 30 are furthermore formed with aligned through openings 37 (see Fig. 5), disposed forwardly of and 5 above the level of openings 35. Said side walls 30 are furthermore formed with aligned arcuate slots 38 having a center of curvature at the axis of the openings 37, and disposed rearwardly thereof. The rectangular side wall portions 31 of sides 30 (Figs. 1, 2 and 6) are formed with aligned lower openings 40 and with aligned upper openings 41 spaced vertically above the lower openings 40. The lower openings 40 are spaced above the level 15 of the slots 32. The side walls 30 are furthermore formed with a plurality of openings 42 (Fig. 2) spaced close to the inclined edges 25, for the purpose hereinafter appearing.

Fixed within the bottom of the frame is a longitudinal filler channel member 50 (Fig. 11). The same comprises a top wall 51 spaced parallelly above the bottom wall 12 (see Figs. 2 and 6). Said top wall has a groove 51a (Fig. 2) at its front end to form a track for a plunger blade, as will appear hereinafter. Extending downwardly from 25 the sides of the top wall 51 parallel side walls 52 (Fig. 6) contacting the inner surfaces of the side walls 13 of the frame member 11 and being spot welded or otherwise fixed thereto. The bottom edges of the side walls 52 of the filler channel member 50 (Fig. 11) contact the top surface of the bottom wall 12 (Fig. 6). Said side walls 52 have tongues 54 projecting downwardly into the opening 16 (Fig. 3), and the ends of the tongue 54 contact the shoulders 18 of the bottom wall 12, so as to prevent longitudinal movement of the inner channel member relative to the frame. At their forward ends, the side walls 52 have downwardly projecting tongues 55, the rear edges of which contact the shoulders 20 of the bottom wall 12. The front edges 56 of the side walls 52 are aligned with the front edges 28 of the side walls 13 of the frame. The top surface of the top wall 51 is at the level of the lower edges of the slots 32, for the purpose hereinafter appearing.

Within the filler channel is an inner staple guide channel 60. The same comprises a bottom wall 61 (see Figs. 1, 2, 6 and 10) contacting the upper surface of the bottom wall 12 and spot welded or otherwise fixed thereto. Extending 50 upwardly from the bottom wall 61 are side walls 62 parallel to and spaced inwardly of the side walls 52 of the filler channel member 50. The bottom wall 61 is cut away as at 63 (see Fig. 11) above the opening 16 in the bottom wall 12 and the side walls 62 thereof are formed with downwardly projecting tongues 64 (Fig. 3) having end edges contacting the shoulders 18 of the bottom wall 12. Said tongue 64 furthermore contacts opposite sides of the tongues 17 (Fig. 3) thereby centering the inner or guide channel 60 relative to the frame and preventing lengthwise movement of said inner channel.

The bottom wall 61 of guide 60 has a front 65 edge 65 (Fig. 1) aligned with the shoulders 20 (Fig. 3) and the side walls 62 are formed at their front ends with downwardly projecting tongues 66 (Figs. 3 and 12) contacting opposite sides of the tongue 19 (Fig. 3) and also contacting at 70 their rear ends the shoulders 20 (Fig. 3) to further center the inner channel relative to the frame.

The front edges 67 (Fig. 3) of the side walls 75 62 of inner guide channel 60 are disposed rear-

wardly of the front edges 28 and 56 (Fig. 3) of the side walls 31 of the body 42 and 52 of the filler channel 50 respectively, to thereby form a throat or track 51b registering with groove 51a (Fig. 2) for a staple.

It will now be understood that the frame 41 together with the filler channel 50 and inner channel 60 constitutes a staple magazine M for a staple strip, not shown. The staple strip is put into the magazine through the rear end thereof and rides on the upper edges of the side walls 62 of the inner channel 60 with the crown of the staple strip contacting said upper edges, and the legs of the staple strip disposed in the spaces between the side walls 62 of the inner channel 60 and the walls 52 of the filler channel 50.

Any suitable pusher means may be provided, not shown, and the rear end of the magazine may be closed in any suitable manner, not shown.

Fitted over the front of the frame 41 is a front cover 70. Said front cover 70 comprises a front wall 71 from which extend rearwardly, parallel side walls 72 (see Fig. 9). The front wall contacts the front edges 28 of the side wall portions 31 of the frame, whereas the side walls 72 contact the outer surfaces of the side wall portions 31. Said front wall 71 has a lower edge 73 (see Fig. 1) substantially at the level of the underside of bottom wall 42. The side walls 72 have lower edges 74 inclined rearwardly and downwardly below the underside of the bottom wall 42. The upper end of the front cover 70 is disposed below the upper edges 27 of the side wall portions 31 of the frame. The upper edges of the side walls 72 are formed with intermediate rectangular notches 75 to receive the outwardly extruded portions or prongs 33 of the frame. Said side walls 72 are furthermore formed with openings 77 aligned with the openings 40 in the side walls 31 to receive a bolt, pin, or rivet 78 therethrough for fixing the front cover to the frame. The front wall 71 is formed with a forwardly recessed vertical portion 78 for the purpose hereinafter appearing. The front wall 71 is formed in its upper end with a central dovetailed notch 79 for the purpose hereinafter appearing.

Fixed to the top of the frame 41 at its forward end is a top cover 80 (see Fig. 2). Said top cover 80 comprises a top wall 81 contacting the upper edges 27 of the side walls 31 of the frame. Extending downwardly from the forward end of the top wall 81 is a front wall 82 in the plane of the front wall 71 of the front cover and contacting its upper edge. Said front wall 82 is formed with a dovetailed extension 83 received in the notch 79 of the front wall 71. Extending downwardly from the top wall 81 are side walls 84. The side walls 84 are formed with through openings 85 registering with the openings 41 in the side walls 31 and extending through said registering openings is a bolt, pin or rivet 86 serving to fix the top cover 80 to the frame.

Extending downwardly and rearwardly from the top wall 81 is a wall portion 87 contacting the curved edges 26 of the frame and extending from said curved wall 87 is a downwardly and rearwardly inclined wall 88 contacting the top edges 25 (Fig. 2). Extending from said wall 88 are side flanges 89 contacting the outer surfaces of the side walls 30 of the frame. Said flanges 89 are formed with openings registering with the openings 42 to receive bolts or screws 90 there-

through for further fixing the top cover to the frame.

Fixed within the front portion of the frame is a combination back stop and bottom stop unit 91. Said unit 91 comprises a bottom wall 92 disposed in the plane of the slots 32 and contacting the top surface of wall 51 of the filler channel 50. Said bottom wall 92 has at its front end, side wings 93 received within the slots 32. Said bottom wall 92 has a front edge 94 contacting the front wall 71 of the front cover 70. The front edge 94 is formed with a groove or slot 95 registering with the groove 51a to form the track or throat for a plunger blade driving the staples, as will appear hereinafter.

Extending upwardly from the bottom wall 92 are parallel side walls 96 contacting the inner surfaces of the side walls 31. Said side walls 96 are formed with vertically aligned openings 97 and 98 registering with the openings 41 and 40, respectively, and receiving therethrough the bolts or pins 86 and 78, respectively, thereby fixing the unit 91 firmly in place within the frame. It will be noted that the front edges 98 and 99 of the side walls 96 are spaced rearwardly from the front edges of the side walls of the frame. The upper ends of the side walls 96 may be at the level of the top edges 27 of the side walls of the frame.

Slidably mounted within the frame and between the front cover and the unit 91 is a plunger assembly 100 (see Fig. 1). Said plunger assembly 100 comprises a box or metal stamping 101. The latter comprises a front wall 102 from which extends rearwardly a bottom wall 103 and parallel side walls 104. The side walls 104 are formed with aligned through openings 105 receiving therethrough a horizontal pin 106 parallel to the front wall 71 of the front cover. The front wall 102 is formed with forwardly pressed or extruded portion 107 for the purpose hereinafter appearing. The rear edges of the side walls 104 slidably engage the front edges 99 of the side walls 96 of the unit 91. Riveted to the front surface of the front wall 102 as by rivet 108 is a plunger blade 109 adapted to project down through the registering grooves 95 and 51a. Said blade 109 is formed with a slot in its upper end to receive the extrusion 107. Said blade 109 contacts the front wall 71 of the front cover. The head of the rivet 108 moves through the recess formed by the forwardly recessed portion 78 of the front wall of the front cover.

Means is provided for driving the plunger when the frame is held by its rear handle end and the forward head end of the frame is swung against a surface into which a staple is to be driven. To this end there extends through the registering openings 35 in the side walls of the frame (see Fig. 10) a bushing 110 contacting the upper surface of top wall 51 of the filler channel 50. Extending through the bushing 110 is a bolt or rivet 111. Pivoted on said bolt 111 is a driver arm or bar 112. The same comprises a pair of parallel side wall portions 113 formed with suitable bearing apertures through which the bolt 111 passes. The bolt 111 may have a head at one end and a nut at the other end contacting the outer surfaces of the side walls 113. The side walls 113 are disposed parallel to and somewhat spaced from the side walls 31 of the frame 41.

Said side walls 113 (see Fig. 4) have lower edges 114 which are inclined downwardly and forwardly to a point below the undersurface of the bottom wall 42 of the frame when the tacker is in normal

position. Said side walls 113 are furthermore formed with upward extensions 115 and the latter are formed with aligned through openings 116 registering with the arcuate slots 38 in the side walls 30 of the frame. In normal position the openings 116 are adjacent the lower ends of the arcuate slots 38.

At the forward ends of the parallel walls 113 are outwardly extending shoulders 117 from which extend forwardly parallel side walls 118 spaced from the side walls 72 of the front cover 70. Said side walls 118 are interconnected by a front wall 119 spaced in front of the front wall 71 of the cover. Extending outwardly from the lower end of the side walls 118 and from the front wall 119 is a flat flange 120 disposed in a plane inclined upwardly and forwardly and disposed below the lower inclined edges 74 of the side walls of the front cover. When the rear handle end of the frame is grasped in the hand, and the front or head end is brought down against a surface S, it is the flange 120 which will strike said surface thereby swinging the driver bar 112 upwardly in a clockwise direction, looking at Fig. 4, about the pivot pin or bolt 111. Said driver bar 112 will move upwardly until the lower surface of the flange 120 comes into the plane of or registers with the forwardly and upwardly inclined edges 74 of the side walls of the front cover, as shown in Fig. 2 of the drawing. Thus, when the tacker is struck against the surface S, the driver bar will move from the position shown in Fig. 1 to the position shown in Fig. 2.

Extending through the apertures or openings 116 in the extensions 115 of the driver bar is a horizontal transverse bolt 121 (see Fig. 5). As the bar is swung upwardly said bolt 121 will move upwardly within the slots 38 (see Fig. 1). The slots 38 are sufficiently wide to provide proper clearance for movement of the bolt 121. Said bolt 121 has a head at one end and a nut at the other end contacting the outer surfaces of wall portions 115 of the driver bar. Surrounding the shank of the bolt and passing through the slots 38 is a bushing 122 serving as a spacer to properly space the wall portions 115.

Extending through the openings 37 in the side walls 30 of the frame is a horizontal transverse pivot pin 125 (see Fig. 5). Surrounding the pivot pin and disposed between said side walls 30 is a bushing 126 having reduced ends. Pivoted on the reduced ends of the bushing is a driver lever 127. Said driver lever 127 comprises a pair of similar symmetrically disposed lever parts 128. Said parts 128 comprise parallel arms 129 substantially contacting the inner surfaces of the side walls 30 of the frame. Said arms 129 are formed with openings 130 to receive the reduced portions of the bushing 126. Said arms 129 are formed adjacent their rear ends with openings 131 to receive therethrough the reduced ends of a bushing 132 surrounding the spacer bushing 122. Extending forwardly from the parallel arms 129 are inclined portions 133 converging toward each other, and extending forwardly therefrom are arms 134 contacting one another and fixed to each other by a pair of transverse rivets 135.

The arms 134 are each formed with a notch 137 at its underedge disposed above the rivet 73 (see Fig. 2). It will be noted that the arms 134 pass between the walls 96 of unit 91, and between the rivets 78 and 86 and into the box 101 above the bottom wall 103 of the latter, and between the side walls 104 thereof. Said arms 134 are formed at their forward ends with registering

slots 138 opening forwardly and receiving therethrough the transverse pin 106.

It will now be understood that as the tacker is struck and the driver bar 112 swings in a clockwise direction relative to the frame, lever 127 will be caused to rotate in a counterclockwise direction relative to the frame, thereby causing the plunger to descend for driving a staple.

It will be observed that when the tacker is fully struck, as shown in Fig. 2, the bottom wall 112 of the frame is inclined rearwardly and upwardly to provide sufficient space beneath the handle of the tacker for the fingers of the operator.

Surrounding the bushing 126 is a torsion spring 140 (Fig. 2 and 13) having one end engaging the bushing 132 and another end hooked about a pin 141, the ends of which are received in the notches 36. The spring tends to rotate the lever 128 in a clockwise direction. After the staple is driven and the tacker is lifted the spring 140 brings all the parts back to their normal position, thereby raising the plunger. The lever will strike the pin 78 just before the bottom wall of the box 101 strikes the bottom stop wall 92 of unit 91. Rivet 86 will be contacted by arms 134 of the lever to limit upward movement of the plunger.

It will now be observed that the pin 78 has three functions. First, it serves to attach the front cover to the frame. Secondly, it serves to fix the unit 91 within the frame, and third, it serves as a stop for the lever 128.

The unit 91 also has several functions. It serves as a back stop for the sliding plunger 100. The bottom wall 92 thereof acts as a bottom stop for the plunger. It also serves to support the top of the filler channel 59, and it furthermore serves to space the side walls of the frame. It also provides a track or throat for the plunger blade 109.

The top pin 86 has several functions. It serves to attach the top cap or cover to the frame. It aids in supporting the back stop for the plunger and it also acts as a top stop for the driver lever.

It will be noted that when the tacker is turned around it can be used as an ordinary hammer and the top wall 81 of the cap or cover 80 serves as a hammer surface when hammering. The dovetailed tongue 83 serves to lock the front cover with the cap. The bushings 126 and 132 are preferably of hardened steel to insure long wearing properties.

It will now be observed that a little movement of the driver bar gives fast movement of the plunger through a greater distance, thereby giving the momentum necessary to drive staples. It will be observed that the bottom flange 120 is flat so that it will not dig into the material or surface being struck. The long fulcrum of the driver bar 112 together with the short movement of the driver bar at the point where it is struck is desirable because it gives speed to the stapling operation.

It will be noted furthermore, that the bushing serves as an additional hold-down for the filler channel 59.

It will thus be seen that there is provided a device in which the several objects of this invention are achieved and which is well adapted to meet the conditions of practical use.

As various possible embodiments might be made of the above invention, and as various changes might be made in the embodiment above set forth, it is to be understood that all matter herein set forth or shown in the accompanying drawings is to be interpreted as illustrative and not in a limiting sense.

Having thus described my invention I claim as new and desire to secure by Letters Patent:

1. A hammer type tacker comprising a frame having a head at one end and a handle extension at the other, a staple magazine within the frame, a plunger slidably mounted within the head of the frame, a driver bar hinged at its rear end to the frame and having a front end disposed below the head of the frame, and adapted to contact a struck surface for rotating said bar about its fulcrum, a lever within the frame pivoted medially the ends thereof to said frame, said lever having a rearwardly extending arm pivoted to an intermediate portion of the driver bar, and said lever having a forwardly extending arm having a pin and slot connection with the plunger.

2. A hammer type tacker comprising a frame having a head at one end and a handle extension at the other, a staple magazine within the frame, a plunger slidably mounted within the head of the frame, a driver bar hinged at its rear end to the frame and having a front end disposed below the head of the frame, and adapted to contact a struck surface for rotating said bar about its fulcrum, a lever within the frame pivoted medially the ends thereof to said frame, said lever having a rearwardly extending arm pivoted to an intermediate portion of the driver bar, and said lever having a forwardly extending arm having a pin and slot connection with the plunger, a front cover on the frame having forwardly and upwardly inclined lower edges, and said driver bar having at its forward end a forwardly and upwardly inclined portion adapted to register with said forwardly and upwardly inclined edges when the device is fully struck against a surface.

3. A hammer type stapler comprising a frame having a head at one end and a handle extension at the other, a plunger slidably mounted for up and down movement within the head of the frame, a driver bar pivoted at its rear end to an intermediate portion of the frame between the head and the handle, said driver bar having at its front end a forwardly and upwardly inclined bottom portion normally disposed below the bottom of the frame, a lever within the frame pivoted medially the ends thereof to said frame and having a rearwardly extending arm pivotally connected to an intermediate portion of the driver bar between the front end and the pivoted end of said driver bar, and said lever having a forwardly extending arm having a pin and slot connection with the plunger.

4. A hammer type stapler comprising a frame having a bottom wall and upwardly extending side walls, said side walls being narrow at their rear ends to provide a handle and increasing in height toward their front ends to form a head, a front cover fitted over the front end of the frame and having a front wall contacting the front edges of the side walls of the frame, and said front cover having side walls contacting the outer surfaces of the side walls of the frame, said side walls of the frame and front cover having registering openings, a transverse pin passing through said registering openings, and a unit disposed between the side walls of the frame and having a horizontal bottom wall and parallel vertical side walls, said side walls of said unit contacting the inner surfaces of the side walls of the frame, and being formed with openings through which said transverse pin passes, and a plunger slidably mounted between the side walls of the frame and located between the front wall of the front cover and the front edges of the side walls of said unit, said plunger comprising a member having a front wall and side walls extending rearwardly therefrom, and a bottom wall extending rearwardly from the lower end of said front wall of said member, and a plunger blade fixed to the front surface of the front wall of said member and extending downwardly therefrom, a pin interconnecting the side walls of said member, a driver bar pivoted at its rear end to the frame substantially midway between the front and rear ends of the latter, and extending forwardly therefrom, said driver bar having a front end disposed below the bottom of the frame, a lever pivoted medially the ends thereof to the frame and having a forwardly projecting arm formed with a slot engaging the transverse pin on said member, and said lever having a rearwardly extending arm pivoted to the driver bar substantially midway between the front and rear ends of the latter.

5. The combination of claim 4, said plunger having a bottom wall located over the said bottom wall of said unit and adapted to strike the bottom wall of said unit when said plunger descends.

10 6. The combination of claim 5, the bottom wall of said unit being formed in the front end with a groove, and said plunger comprising a plunger blade received within said groove.

7. The combination of claim 4, in combination with a staple magazine fixed within the bottom of said frame between the bottom wall of said frame and the side walls of said frame, and the bottom wall of said unit contacting the top of said staple magazine.

8. The combination of claim 4, in combination with a spring actuated lever pivoted to the frame and connected to said plunger, and a driver bar pivoted to the frame and lever and having a portion projecting below the front end of said frame.

20 9. A hammer type stapler comprising a frame having a bottom wall and upwardly extending side walls, said side walls being narrow at their rear ends to provide a handle and increasing in height toward their front ends to form a head, a front cover fitted over the front end of the frame and having a front wall contacting the front edges of the side walls of the frame, and said front cover having side walls contacting the outer surfaces of the side walls of the frame, said side walls of the frame and front cover having registering openings, a transverse pin passing through said registering openings, and a unit disposed between the side walls of the frame and having a horizontal bottom wall and parallel vertical side walls, said side walls of said unit contacting the inner surfaces of the side walls of the frame, and being formed with openings through which said transverse pin passes, and a plunger slidably mounted between the side walls of the frame and located between the front wall of the front cover and the front edges of the side walls of said unit, said plunger comprising a member having a front wall and side walls extending rearwardly therefrom, and a bottom wall extending rearwardly from the lower end of said front wall of said member, and a plunger blade fixed to the front surface of the front wall of said member and extending downwardly therefrom, a pin interconnecting the side walls of said member, a driver bar pivoted at its rear end to the frame substantially midway between the front and rear ends of the latter, and extending forwardly therefrom, said driver bar having a front end disposed below the bottom of the frame, a lever pivoted medially the ends thereof to the frame and having a forwardly projecting arm formed with a slot engaging the transverse pin on said member, and said lever having a rearwardly extending arm pivoted to the driver bar substantially midway between the front and rear ends of the latter.

40 10. A hammer type stapler comprising a frame having a bottom wall and upwardly extending side walls, said side walls being narrow at their rear ends to provide a handle and increasing in height toward their front ends to form a head, a front cover fitted over the front end of the frame and having a front wall contacting the front edges of the side walls of the frame, and said front cover having side walls contacting the outer surfaces of the side walls of the frame, said side walls of the frame and front cover having reg-

50 65 70 75

istering openings, a transverse pin passing through said registering openings, and a unit disposed between the side walls of the frame and having a horizontal bottom wall and parallel vertical side walls, said side walls of said unit contacting the inner surfaces of the side walls of the frame, and being formed with openings through which said transverse pin passes, and a plunger slidably mounted between the side walls of the frame and located between the front wall of the front cover and the front edges of the side walls of said unit, said plunger comprising a member having a front wall and side walls extending rearwardly therefrom, and a bottom wall extending rearwardly from the lower end of said front wall of said member, and a plunger blade fixed to the front surface of the front wall of said member and extending downwardly therefrom, a pin interconnecting the side walls of said member, a driver bar pivoted at its rear end to the frame substantially midway between the front and rear ends of the latter, and extending forwardly therefrom, said driver bar having a front end disposed below the bottom of the frame, a lever pivoted medially the ends thereof to the frame and having a forwardly projecting arm formed with a slot engaging the transverse pin on said member, and said lever having a rearwardly extending arm pivoted to the driver bar substantially midway between the front and rear ends of the latter, a filler channel fixed within said frame and between the side walls of the frame and having a top wall and downwardly extending side walls, the side walls of the filler channel contacting the inner surfaces of the side walls of the frame, and the bottom wall of said unit contacting the top wall of said filler channel.

11. A hammer type stapler comprising a frame having a bottom wall and upwardly extending side walls, said side walls being narrow at their rear ends to provide a handle and increasing in height toward their front ends to form a head, a front cover fitted over the front end of the frame and having a front wall contacting the front edges of the side walls of the frame, and said front cover having side walls contacting the outer surfaces of the side walls of the frame, said side walls of the frame and front cover having registering openings, a transverse pin passing through said registering openings, and a unit disposed between the side walls of the frame and having a horizontal bottom wall and parallel vertical side walls, said side walls of said unit contacting the inner surfaces of the side walls of the frame, and being formed with openings through which said transverse pin passes, and a plunger slidably mounted between the side walls of the frame and located between the front wall of the front cover and the front edges of the side walls of said unit, said plunger comprising a member having a front wall and side walls extending rearwardly therefrom, and a bottom wall extending rearwardly from the lower end of said front wall of said member, and a plunger blade fixed to the front surface of the front wall of said member and extending downwardly therefrom, a pin interconnecting the side walls of said member, a driver bar pivoted at its rear end to the frame substantially midway between the front and rear ends of the latter, and extending forwardly therefrom, said driver bar having a front end disposed below the bottom of the frame, a lever pivoted medially the ends thereof to the frame and having a forwardly projecting arm formed with a slot engaging the transverse pin on said member, and said lever having a rearwardly extending arm pivoted to the driver bar substantially midway between the front and rear ends of the latter, a filler channel fixed within said frame and between the side walls of the frame and having a top wall and downwardly extending side walls, the side walls of the filler channel contacting the inner surfaces of the side walls of the frame, and the bottom wall of said unit contacting the top wall of said filler channel, the top wall of the filler channel and the bottom wall of said unit being formed with registering grooves through which the plunger blade may pass.

on said member, and said lever having a rearwardly extending arm pivoted to the driver bar substantially midway between the front and rear ends of the latter, a filler channel fixed within said frame and between the side walls of the frame and having a top wall and downwardly extending side walls, the side walls of the filler channel contacting the inner surfaces of the side walls of the frame, and the bottom wall of said unit contacting the top wall of said filler channel, the pivot between the driver bar and the frame comprising a transverse pin, and a bushing thereon contacting the top wall of said filler channel.

12. A hammer type stapler comprising a frame having a bottom wall and upwardly extending side walls, said side walls being narrow at their rear ends to provide a handle and increasing in height toward their front ends to form a head, a front cover fitted over the front end of the frame and having a front wall contacting the front edges of the side walls of the frame, and said front cover having side walls contacting the outer surfaces of the side walls of the frame, said side walls of the frame and front cover having registering openings, a transverse pin passing through said registering openings, and a unit disposed between the side walls of the frame and having a horizontal bottom wall and parallel vertical side walls, said side walls of said unit contacting the inner surfaces of the side walls of the frame, and being formed with openings through which said transverse pin passes, and a plunger slidably mounted between the side walls of the frame and located between the front wall of the front cover and the front edges of the side walls of said unit, said plunger comprising a member having a front wall and side walls extending rearwardly therefrom, and a bottom wall extending rearwardly from the lower end of said front wall of said member, and a plunger blade fixed to the front surface of the front wall of said member and extending downwardly therefrom, a pin interconnecting the side walls of said member, a driver bar pivoted at its rear end to the frame substantially midway between the front and rear ends of the latter, and extending forwardly therefrom, said driver bar having a front end disposed below the bottom of the frame, a lever pivoted medially the ends thereof to the frame and having a forwardly projecting arm formed with a slot engaging the transverse pin on said member, and said lever having a rearwardly extending arm pivoted to the driver bar substantially midway between the front and rear ends of the latter, a filler channel fixed within said frame and between the side walls of the frame and having a top wall and downwardly extending side walls, the side walls of the filler channel contacting the inner surfaces of the side walls of the frame, and the bottom wall of said unit contacting the top wall of said filler channel, the top wall of the filler channel and the bottom wall of said unit being formed with registering grooves through which the plunger blade may pass.

13. A hammer type stapler comprising a frame having a bottom wall and upwardly extending side walls, said side walls being narrow at their rear ends to provide a handle and increasing in height toward their front ends to form a head, a front cover fitted over the front end of the frame and having a front wall contacting the front edges of the side walls of the frame, and said front cover having side walls contacting the outer surfaces of the side walls of the frame, said

side walls of the frame and front cover having registering openings, a transverse pin passing through said registering openings, and a unit disposed between the side walls of the frame and having a horizontal bottom wall and parallel vertical side walls, said side walls of said unit contacting the inner surfaces of the side walls of the frame, and being formed with openings through which said transverse pin passes, and a plunger slidably mounted between the side walls of the frame and located between the front wall of the front cover and the front edges of the side walls of said unit, said plunger comprising a member having a front wall and side walls extending rearwardly therefrom, and a bottom wall extending rearwardly from the lower end of said front wall of said member, and a plunger blade fixed to the front surface of the front wall of said member and extending downwardly therefrom, a pin interconnecting the side walls of said member, a driver bar pivoted at its rear end to the frame substantially midway between the front and rear ends of the latter, and extending forwardly therefrom, said driver bar having a front end disposed below the bottom of the frame, a lever pivoted medially the ends thereof to the frame and having a forwardly projecting arm formed with a slot engaging the transverse pin on said member, and said lever having a rearwardly extending arm pivoted to the driver bar substantially midway between the front and rear ends of the latter, and the side walls of the frame being formed with slots through which pass the pivotal connection between the rearwardly extending arm of said lever and said driver bar.

14. A hammer type stapler comprising a frame having a bottom wall and upwardly extending side walls, and having front edges, a front cover having a front wall contacting the front edges of the side walls of the frame, and said front cover having side walls contacting the outer surfaces of the side walls of said frame, the side walls of said frame and front cover having registering openings, and a transverse pin passing through said openings to fix the front cover to the frame, and a unit within the frame having a bottom wall and upwardly extending side walls, the side walls of said unit contacting the inner surfaces of the side walls of the frame and having openings through which said transverse pin passes, a staple magazine on the bottom wall of the frame and between its side walls, and the bottom wall of said unit contacting the top of said magazine.

15. The combination of claim 14, in combination with a plunger slidably within the frame and between the front edges of the side walls of said unit and the front wall of the cover, and a portion of said plunger overlying the bottom wall of said unit and a lever pivoted meditately the ends thereof, to said frame, the front end of said lever being connected to said plunger and an operating bar pivoted at its rear end to the frame and at an intermediate portion thereof to the rear end of the lever and said actuating bar having a portion at its front end normally disposed below the front end of the frame.

16. A hammer type stapler comprising a frame having a bottom wall and upwardly extending side walls, and having front edges, a front cover having a front wall contacting the front edges of the side walls of the frame, and said front cover having side walls contacting the outer surfaces of the side walls of said frame, the side walls of said frame and front cover having registering

openings, and a transverse pin passing through said openings to fix the front cover to the frame, and a unit within the frame having a bottom wall and upwardly extending side walls, the side walls of said unit contacting the inner surfaces of the side walls of the frame and having openings through which said transverse pin passes, and a plunger slidably mounted within said frame and between the side walls of the frame and having a portion contacting the front edges of the side walls of said unit and disposed above the bottom wall of said unit.

17. A hammer type stapler comprising a frame having a bottom wall and upwardly extending side walls, and having front edges, a front cover having a front wall contacting the front edges of the side walls of the frame, and said front cover having side walls contacting the outer surfaces of the side walls of said frame, the side walls of said frame and front cover having registering openings, and a transverse pin passing through said openings to fix the front cover to the frame, and a unit within the frame having a bottom wall and upwardly extending side walls, the side walls of said unit contacting the inner surfaces of the side walls of the frame and having openings through which said transverse pin passes, and a plunger slidably mounted within said frame and between the side walls of the frame and having a portion contacting the front edges of the side walls of said unit and disposed above the bottom wall of said unit, said bottom wall having a groove at its front end and said plunger including a plunger blade passing through said groove.

18. A hammer type stapler comprising a frame having a bottom wall and upwardly extending side walls, and having front edges, a front cover having a front wall contacting the front edges of the side walls of the frame, and said front cover having side walls contacting the outer surfaces of the side walls of said frame, the side walls of said frame and front cover having registering openings, and a transverse pin passing through said openings to fix the front cover to the frame, and a unit within the frame having a bottom wall and upwardly extending side walls, the side walls of said unit contacting the inner surfaces of the side walls of the frame and having openings through which said transverse pin passes, and a plunger slidably mounted within said frame and between the side walls of the frame and having a portion contacting the front edges of the side walls of said unit and disposed above the bottom wall of said unit, a lever pivoted meditately the ends thereof to said frame and having a forwardly extending arm having a pin and slot connection with said plunger, and said lever having a rearwardly extending arm, a driver bar pivoted at its rear end to the frame rearwardly of said lever, said driver bar having a front end normally disposed below said frame, and a pivot pin interconnecting the rearwardly extending arm of said lever with an intermediate portion of said driver bar, and the side walls of said frame having slots through which said last mentioned pivot pin passes.

19. A hammer type stapler comprising a frame having a bottom wall and upwardly extending side walls, and having front edges, a front cover having a front wall contacting the front edges of the side walls of the frame, and said front cover having side walls contacting the outer surfaces of the side walls of said frame, the side walls of said frame and front cover having registering openings, and a transverse pin passing through

said openings to fix the front cover to the frame, and a unit within the frame having a bottom wall and upwardly extending side walls, the side walls of said unit contacting the inner surfaces of the side walls of the frame and having openings through which said transverse pin passes, and a plunger slidably mounted within said frame and between the side walls of the frame and having a portion contacting the front edges of the side walls of said unit and disposed above the bottom wall of said unit, a lever pivoted medially the ends thereof to said frame and having a forwardly extending arm having a pin and slot connection with said plunger, and said lever having a rearwardly extending arm, a driver bar pivoted at its rear end to the frame rearwardly of said lever, said driver bar having a front end normally disposed below said frame, and a pivot pin interconnecting the rearwardly extending arm of said lever with an intermediate portion of said driver bar, and the side walls of said frame having slots through which said last mentioned pivot pin passes, the first mentioned transverse pin being so located as to engage the underedge of the forwardly extending arm of said lever to limit downward movement of the plunger.

20. A hammer type stapler comprising a frame having a bottom wall and upwardly extending side walls, and having front edges, a front cover having a front wall contacting the front edges of the side walls of the frame, and said front cover having side walls contacting the outer surfaces of the side walls of said frame, the side walls of said frame and front cover having registering openings, and a transverse pin passing through said openings to fix the front cover to the frame, and a unit within the frame having a bottom wall and upwardly extending side walls, the side walls of said unit contacting the inner surfaces of the side walls of the frame and having openings through which said transverse pin passes, and a plunger slidably mounted within said frame and between the side walls of the frame and having a portion contacting the front edges of the side walls of said unit and disposed above the bottom wall of said unit, a lever pivoted medially the ends thereof to said frame and having a forwardly extending arm having a pin and slot connection with said plunger, and said lever having a rearwardly extending arm, a driver bar pivoted at its rear end to the frame rearwardly of said lever, said driver bar having a front end normally disposed below said frame, and a pivot pin interconnecting the rearwardly extending arm of said lever with an intermediate portion of said driver bar, and the side walls of said frame having slots through which said last mentioned pivot pin passes, the first mentioned transverse pin being so located as to engage the underedge of the forwardly extending arm of said lever to limit downward movement of the plunger, the side walls of said frame being interconnected by a top transverse pin passing through openings in the side walls of said unit, and said top pin serving to contact the top of the forwardly extending arm of said lever to serve as a stop for the upward movement of said plunger.

ward movement of said plunger.

21. A hammer type stapler comprising a frame having a bottom wall and upwardly extending side walls, and having front edges, a front cover having a front wall contacting the front edges of the side walls of the frame, and said front cover having side walls contacting the outer surfaces of the side walls of said frame, the side walls of said frame and front cover having reg-

istering openings, and a transverse pin passing through said openings to fix the front cover to the frame, and a unit within the frame having a bottom wall and upwardly extending side walls, the side walls of said unit contacting the inner surfaces of the side walls of the frame and having openings through which said transverse pin passes, and a plunger slidably mounted within said frame and between the side walls of the frame and having a portion contacting the front edges of the side walls of said unit and disposed above the bottom wall of said unit, a lever pivoted medially the ends thereof to said frame and having a forwardly extending arm having a pin and slot connection with said plunger, and said lever having a rearwardly extending arm, a driver bar pivoted at its rear end to the frame rearwardly of said lever, said driver bar having a front end normally disposed below said frame, and a pivot pin interconnecting the rearwardly extending arm of said lever with an intermediate portion of said driver bar, and the side walls of said frame having slots through which said last mentioned pivot pin passes, the first mentioned transverse pin being so located as to engage the underedge of the forwardly extending arm of said lever to limit downward movement of the plunger, the side walls of said frame being interconnected by a top transverse pin passing through openings in the side walls of said unit, and said top pin serving to contact the top of the forwardly extending arm of said lever to serve as a stop for the upward movement of said plunger, and a top cap on the top of the forward end of said frame and having a top wall contacting the upper edges of the side walls of said unit and said top cap having side flanges formed with openings through which the top pin passes.

22. A hammer type stapler comprising a frame having a bottom wall and upwardly extending side walls, and having front edges, a front cover having a front wall contacting the front edges of the side walls of the frame, and said front cover having side walls contacting the outer surfaces of the side walls of said frame, the side walls of said frame and front cover having registering openings, and a transverse pin passing through said openings to fix the front cover to the frame, and a unit within the frame having a bottom wall and upwardly extending side walls, the side walls of said unit contacting the inner surfaces of the side walls of the frame and having openings through which said transverse pin passes, and a plunger slidably mounted within said frame and between the side walls of the frame and having a portion contacting the front edges of the side walls of said unit and disposed above the bottom wall of said unit, a lever pivoted medially the ends thereof to said frame and having a forwardly extending arm having a pin and slot connection with said plunger, and said lever having a rearwardly extending arm, a driver bar pivoted at its rear end to the frame rearwardly of said lever, said driver bar having a front end normally disposed below said frame, and a pivot pin interconnecting the rearwardly extending arm of said lever with an intermediate portion of said driver bar, and the side walls of said frame having slots through which said last mentioned pivot pin passes, the first mentioned transverse pin being so located as to engage the underedge of the forwardly extending arm of said lever to limit downward movement of the plunger, the side walls of said frame being interconnected by a top transverse pin passing through openings in

the side walls of said unit, and said top pin serving to contact the top of the forwardly extending arm of said lever to serve as a stop for the upward movement of said plunger, and a top cap on the top of the forward end of said frame and having a top wall contacting the upper edges of the side walls of said unit and said top cap having side flanges formed with openings through which the top pin passes, said top cap having a front wall having a dovetailed joint with the front wall of said front cover.

23. A hammer type stapler comprising a frame having a bottom wall and upwardly extending side walls, and having front edges, a front cover having a front wall contacting the front edges of the side walls of the frame, and said front cover having side walls contacting the outer surfaces of the side walls of said frame, the side walls of said frame and front cover having registering openings, and a transverse pin passing through said openings to fix the front cover to the frame, and a unit within the frame having a bottom wall and upwardly extending side walls, the side walls of said unit contacting the inner surfaces of the side walls of the frame and having openings through which said transverse pin passes, and a plunger slidably mounted within said frame and between the side walls of the frame and having a portion contacting the front edges of the side walls of said unit and disposed above the bottom wall of said unit, a lever pivoted medially the ends thereof to said frame and having a forwardly extending arm having a pin and slot connection with said plunger, and said lever having a rearwardly extending arm, a driver bar pivoted at its rear end to the frame rearwardly of said lever, said driver bar having a front end normally disposed below said frame, and a pivot pin interconnecting the rearwardly extending arm of said lever with an intermediate portion of said driver bar, and the side walls of said frame having slots through which said last mentioned pivot pin passes, the first mentioned transverse pin being so located as to engage the underedge of the forwardly extending arm of said lever to limit downward movement of the plunger, the side walls of said frame being interconnected by a top transverse pin passing through openings in the side walls of said unit, and said top pin serving to contact the top of the forwardly extending arm of said lever to serve as a stop for the upward movement of said plunger, and a top cap on the top of the forward end of said frame and having a top wall contacting the upper edges of the side walls of said unit and said top cap having side flanges formed with openings through which the top pin passes, said top cap having a front wall having a dovetailed joint with the front wall of said front cover, said side walls of the frame having outwardly projecting extruded portions received in notches in the upper edges of the side walls of the front cover.

24. A hammer type stapler comprising a frame having a bottom wall and upwardly extending side walls, and having front edges, a front cover having a front wall contacting the front edges of the side walls of the frame, and said front cover having side walls contacting the outer surfaces of the side walls of said frame, the side walls of said frame and front cover having registering openings, and a transverse pin passing through said openings to fix the front cover to the frame, and a unit within the frame having a bottom wall and upwardly extending side walls,

the side walls of said unit contacting the inner surfaces of the side walls of the frame and having openings through which said transverse pin passes, and a plunger slidably mounted within said frame and between the side walls of the frame and having a portion contacting the front edges of the side walls of said unit and disposed above the bottom wall of said unit, said bottom wall having a groove at its front end and said plunger including a plunger blade passing through said groove, the side walls of said frame having slots and the bottom wall of said unit having horizontal wings received in said slots.

25. A hammer type stapler comprising a frame having a bottom wall and upwardly extending side walls, and having front edges, a front cover having a front wall contacting the front edges of the side walls of the frame, and said front cover having side walls contacting the outer surfaces of the side walls of said frame, the side walls of said frame and front cover having registering openings, and a transverse pin passing through said openings to fix the front cover to the frame, and a unit within the frame having a bottom wall and upwardly extending side walls, the side walls of said unit contacting the inner surfaces of the side walls of the frame and having openings through which said transverse pin passes, and a plunger slidably mounted within said frame and between the side walls of the frame and having a portion contacting the front edges of the side walls of said unit and disposed above the bottom wall of said unit, a lever pivoted medially the ends thereof to said frame and having a forwardly extending arm having a pin and slot connection with said plunger, and said lever having a rearwardly extending arm, a driver bar pivoted at its rear end to the frame rearwardly of said lever, said driver bar having a front end normally disposed below said frame, and a pivot pin interconnecting the rearwardly extending arm of said lever with an intermediate portion of said driver bar, and the side walls of said frame having slots through which said last mentioned pivot pin passes, the first mentioned transverse pin being so located as to engage the underedge of the forwardly extending arm of said lever to limit downward movement of the plunger, the side walls of said frame being interconnected by a top transverse pin passing through openings in the side walls of said unit, and said top pin serving to contact the top of the forwardly extending arm of said lever to serve as a stop for the upward movement of said plunger, and a top cap on the top of the forward end of said frame and having a top wall contacting the upper edges of the side walls of said unit and said top cap having side flanges formed with openings through which the top pin passes, said top cap having a front wall having a dovetailed joint with the front wall of said front cover, said side walls of the frame having outwardly projecting extruded portions received in notches in the upper edges of the side walls of the front cover.

26. A hammer type stapler comprising a frame provided with a rearwardly extending handle, a plunger slidably up and down, at the front of the frame, a lever pivoted medially the ends thereof to said frame, the said lever having an operating connection at its front end, to the plunger, a driver bar pivoted at its near end to said frame, rearwardly of the lever, means to pivotally connect an intermediate portion of the operating bar to the rear end of the lever, said driver bar having a front end projecting below the front end of the frame.

27. The combination of claim 26, in combination with spring means to rotate the lever in a direction for raising the front end of the lever to lift said plunger.

28. The combination of claim 26, said front end of said driver bar being inclined upwardly and forwardly relative to the plane of the underside of the frame.

29. The combination of claim 28, in combination with spring means to rotate the lever in a direction to raise the front end of the lever to lift the plunger.

30. A hammer type stapler comprising a frame, a plunger slidably mounted within the frame at the front end of the latter, a plunger blade fixed to said plunger and extending downwardly therefrom, said plunger having side walls, a pin interconnecting said side walls of said plunger, a

driver bar pivoted at its rear end to the frame substantially mid-way between the front and rear ends of the frame, said driver bar having a front end disposed below the bottom of the front end of the frame, a lever pivoted medially the ends thereof to the frame and having a forwardly projecting arm formed with a slot engaging a transverse pin on said plunger, and said lever having a rearwardly extending arm pivoted to the driver bar substantially mid-way between the front and rear ends of said bar.

31. A hammer type stapler comprising a frame having a bottom wall and upwardly extending side walls, said side walls being narrow at their rear ends to provide a handle and increasing in height toward their front ends to form a head, a front cover fitted over the front end of the frame and having a front wall contacting the front edges of the side walls of the frame, and said front cover having side walls contacting the outer surfaces of the side walls of the frame, said side walls of the frame and front cover having registering openings, a transverse pin passing through said registering openings, and a unit disposed between the side walls of the frame and having a horizontal bottom wall and parallel vertical side walls, said side walls of said unit contacting the inner surfaces of the side walls of the frame, and being formed with openings through which said transverse pin passes, a plunger slidably mounted between the side walls of the frame and located between the front wall of the front cover and the front edges of the side walls of said unit, said plunger comprising a member having a front wall and side walls extending rearwardly therefrom, and a bottom wall extending rearwardly from the lower end of the front wall of said member, and the plunger blade fixed to the front surface of the plunger wall of said member extending downwardly therefrom, means to reciprocate said plunger up and down, a filler channel fixed within said frame and between the side walls of the frame and having a top wall and downwardly extending side walls, the side walls of the filler channel contacting the inner surface of the side wall of the frame, and the bottom wall of said unit contacting the top wall of said filler channel.

32. The combination of claim 31, the top wall of the filler channel and the bottom wall of said unit being formed with registering grooves through which the plunger blade passes.

33. A hammer type stapler comprising a frame, provided with side walls, a unit within the frame

having a bottom wall and upwardly extending side walls contacting the inner surfaces of the side walls of the frame, means to attach said unit to said frame, a plunger slidably mounted within the frame and slidably engaging the front edges of the side walls of the unit, a lever pivoted medially to the ends thereof, to said frame, and having a forwardly extending arm operatively connected with said plunger, said lever having a rearwardly extending arm, a driver bar pivoted at its rear end to the frame rearwardly of the lever, said driver bar having a front end normally disposed below the front end of said frame, and means to interpivot the rearwardly extending arm of said lever in the intermediate portion of said driver bar.

34. A hammer type stapler comprising a frame provided with side walls, a plunger slidably up and down between said side walls at the front end of the frame, a pivoted pin interconnecting said side walls, a lever disposed between the side walls of the frame, said pivot pin passing through said lever, the front end of the lever being connected by a pin and slot connection to said plunger, a driver bar having side walls disposed at the outer sides at the side walls of the frame, means to pivot the rear ends of the side walls of the driver bar, the rear end of the lever being pivotally connected to medial portions of the side walls of said bar by means of the pivot pin passing through slots formed in the side walls of the frame.

35. The combination of claim 34, the side walls of the driver bar being formed at their front ends with portions inclined upwardly and forwardly relative to the underside of said frame.

36. The combination of claim 34, the front ends of the side walls of said bar and the portion interconnecting the side walls of said bar being provided with flanges disposed in a plane inclined upwardly and forwardly relatively to the underside of said frame.

MORRIS ABRAMS.
